UNITED STATES PATENT OFFICE.

MARTIN R. CROSSMAN, OF BOSTON, MASSACHUSETTS.

FOUNTAIN-PEN.

No. 810,327.

Specification of Letters Patent.

Patented Jan. 16, 1906.

Application filed May 29, 1905. Serial No. 262,791.

To all whom it may concern:

Be it known that I, MARTIN R. CROSSMAN, a citizen of the United States, and a resident of Boston, county of Suffolk, and State of Massachusetts, have invented an Improvement in Fountain-Pens, of which the following description, in connection with the accompanying drawings, is a specification, like numerals on the drawings representing like parts.

10 This invention relates to fountain-pens, and particularly to a device for preventing pens from "sweating."

Most fountain-pens "sweat" more or less, (this term being used to describe the film or 15 coating of ink which gathers between the holder and the cap when the cap is covering the pen-point) and whenever a pen does sweat in this way it becomes necessary to wipe the ink from the outside of the holder before 20 the pen can be used.

I have provided a novel "antisweating" device which can be applied to any pen and which by its presence prevents all leaking or sweating.

25 My improved device is in the nature of a cap, which fits tightly over the pen-point and covers the air-holes therein, and thus prevents either escape of ink from the holder or the admission of air thereto. The cap is made to 30 fit tightly over the pen-point. Therefore its presence does not interfere in any way with the operation of removing or replacing the regular cap for the holder.

When in use, my improved antisweating- 35 cap is supported and carried entirely by the pen-point and does not contact with the regular cap for the holder.

In the drawings, Figure 1 shows a fountain-pen having my improvements applied thereto, 40 the cap for the holder being shown in section. Fig. 2 is a section on an enlarged scale on the line $\alpha\alpha$, Fig. 1. Fig. 3 is a view of the anti-sweating-cap. Fig. 4 is a view of a holder-clip which is especially constructed to support my antisweating-cap when the latter is 45 not in use.

3 designates the holder or barrel of a fountain-pen; 4, the usual cap which covers the pen-point when the pen is not in use; 5, the 50 pen-point, and 6 the feed-bar. These parts are or may be of any suitable or usual construction and form no part of my present invention. My invention resides in a cap which is entirely distinct and separate from 55 the regular cap 4 and which is of a shape to

tightly fit over the pen-point 5. In the drawings, 7 designates this cap, which I have referred to as an "antisweating-cap." The cap 7, it will be seen, fits tightly over the back of the pen-point 5 and closes the air-hole and 60 the slit with which all pens are provided. The cap 7 may be made of any suitable material. A metal cap which had the proper shape to tightly fit over the pen-point would embody my invention; but it will be obvious that 65 a cap made of some non-yielding material would fit only a certain size and shape of pen, and to equip a variety of pens with my invention would necessitate the making of a considerable number of caps 7 of different shapes. 70 I prefer, therefore, to make the cap 7 of some yielding material—such, for instance, as rubber—so that a certain sized cap can be used with pens of different sizes and shapes. I prefer also to make the cap substantially 75 conical in shape, as shown in the drawings. It will be understood, of course, that the cap is closed at its end.

When a cap embodying my invention is placed on the pen-point of a fountain-pen, the 80 air-hole and the slit of said pen are closed, and therefore no ink can escape from the pen, nor can any air get into the holder. It will be impossible, therefore, for the pen to sweat—that is, for the ink to gather between the cap 85 and the holder. Another result which follows from the use of my invention is that the cap 7 when in place keeps the pen-point moist so that the pen is ready for use the instant that the cap is removed. I prefer to provide 90 the base or mouth of the cap with the bead or thickened portion 15, which causes the cap when in place to hug the pen more tightly.

My invention also includes a novel holder or support for the cap 7 when the pen is in 95 use. Referring to Fig. 4, 10 designates a suitable clip, which may be secured in some suitable way to the cap 4 of pen and by means of which the pen is retained in the pocket. I have provided this clip with a tubular holder 100 11, which is adapted to receive the pointed end 12 of the cap, all as shown in Fig. 4. My invention, however, is not limited to the form of holder shown herein, as any suitable means for supporting the cap 7 when the pen is in 105 use may be employed.

Various changes in the construction of the cap and its holder may be made without departing from my invention.

My improved device will also prevent the 110

pen from leaking if by chance it is carried bottom side up.

Having fully described my invention, what I claim as new, and desire to secure by Letters 5 Patent, is—

In a fountain-pen, a holder, a pen-point, a cap to fit over the holder and pen-point, an antisweating-cap of a size to be received within first-mentioned cap and of a shape to fit 10 tightly over the pen-point and means carried

by the pen to sustain said antisweating-cap when the latter is not in use.

In testimony whereof I have signed my name to this specification in the presence of two subscribing witnesses.

MARTIN R. CROSSMAN.
